CLAIM

The ornamental design for an electronic device display screen with animated graphical user interface as shown and described.

DESCRIPTION

FIG. 1 is a front view of an electronic device having a display screen with an animated graphical user interface showing a first image in a sequence according to my new design;

FIG. 2 is a front view thereof showing the second image in the sequence;

FIG. 3 is a front view thereof showing the third image in the sequence;

FIG. 4 is a front view thereof showing the fourth image in the sequence; and,

FIG. 5 is a front view thereof showing the fifth image in the sequence.

The outermost of the two outer broken-line rectangles shows an electronic device. The inner of the two rectangles shows a perimeter of a display screen. The other broken lines show portions of the graphical user interface. The broken lines form no part of the claimed design.

The appearance of the animated image sequentially transitions between the images shown in FIGS. 1-5. The process or period in which one image transitions to another forms no part of the claimed design.

1 Claim, 5 Drawing Sheets
